US00D592701S

(12) **United States Design Patent**
Matsushita et al.

(10) **Patent No.:** US D592,701 S
(45) **Date of Patent:** ** May 19, 2009

(54) **REFILL FOR COATING FILM TRANSFER
TOOL**

(75) Inventors: **Kinya Matsushita**, Osaka (JP); **Hideto Shima**, Yawata (JP)

(73) Assignee: **Kokuyo S&T Co., Ltd.**, Osaka (JP)

(**) Term: **14 Years**

(21) Appl. No.: **29/228,206**

(22) Filed: **Apr. 21, 2005**

(30) **Foreign Application Priority Data**

Nov. 4, 2004 (JP) D2004-033504

(51) **LOC (9) Cl.** **19-02**

(52) **U.S. Cl.** **D19/67**

(58) **Field of Classification Search** D19/66, D19/67, 68, 69, 70; 156/523, 257, 540, 577; 206/411; 225/6, 25, 39, 77; 242/588, 588.1, 242/588.2, 588.3, 588.6, 598.5

(57) **CLAIM**

The ornamental design for a refill for coating film transfer tool, as shown and described.

DESCRIPTION

FIG. 1 is a front elevational view of a refill for coating film transfer tool showing our new design;

FIG. 2 is a rear elevational view;

FIG. 3 is a top plan view;

FIG. 4 is a bottom plan view;

FIG. 5 is a right side elevational view; and,

FIG. 6 is a left side elevational view.

The broken line showings are for illustrative purposes only and form no part of the claimed design.
